TOY POWER SHOVEL

Allan J. Alvaney, Arlington Heights, Ill., assignor to Sears, Roebuck and Co., Chicago, Ill., a corporation of New York

Filed Sept. 6, 1960, Ser. No. 62,027

Term of patent 7 years

(Cl. D34—15)

FIG. 1 is a side elevational view of a toy power shovel embodying my new design;

FIG. 2 is a top plan view of the same;

FIG. 3 is a front elevational view thereof;

FIG. 4 is a rear elevational view of the same, the lower portion thereof, which is substantially similar to the corresponding portion shown in FIG. 3, being shown fragmentarily, and

FIG. 5 is a fragmentary elevational view of the side opposite that shown in FIG. 1, the parts not shown being substantially similar to the corresponding parts shown in FIG. 1.

The essential features of my design reside in the portions shown in full lines.

I claim:

The ornamental design for a toy power shovel, substantially as shown and described.
